ROTARY ROCK DISK BIT

James W. Sperry, South Pasadena, Calif.

Application October 4, 1929, Serial No. 397,238

4 Claims. (Cl. 255—71)

This invention relates to bits of the character employed in drilling wells by the rotary system of drilling, in which a cutting tool is rotated on the lower end of a vertical drilling shaft 5 consisting generally of a string of drill pipe extending into the well and rotated by rotary apparatus situated at the top of the well.

In the rotary method of drilling wells, cutting away or displacement of the subterranean formations is accomplished by one or the other of, or the combination of, two operations which are: first, a scraping or slicing operation, such as produced by the fist-tail bit, and second, a pounding or crushing operation, such as accomplished by rock bits having toothed rollers which roll in engagement with the formation.

It is an object of the invention to provide a new form of disk bit which may be employed to cut hard formations and which is so designed 10 that a combined impact and slicing operation is accomplished by the disk cutters thereof.

A further object of the invention is to provide a rotary disk bit having a simple and rugged bit body consisting essentially of a single 15 unitary structure having no parts which may become displaced and lost in the well.

A further object of the invention is to provide a disk bit of this character with simple means for removably supporting the replaceable cutter 20 disk and cutter disk bearings.

A further object of the invention is to provide a bit of this character having a central supporting leg and having a fluid passage extending vertically and centrally through said 25 supporting leg so as to deliver a fluid, such as the mud and water mixtures employed in rotary drilling, against the central core formed by the disk bit when it is operated, so as to remove or assist in removing such central core.

A further object of the invention is to provide a bit of this character having integrally formed supporting legs, a laterally extending supporting bar of non-circular cross section extending through and supported in the lower end 30 of said legs, and bearing members having non-circular openings therein positioned so as to hold said bearing members on the supporting bar in a desired axially offset co-relationship. In the practice of the invention I may support 35 the bearing members non-rotatably on a supporting bar of circular cross section by providing an interengagement between the bearing members and a stationary portion of the bit body.

Further objects and advantages of the inven-

tion will be made evident throughout the following part of the specification.

Referring to the drawings which are for illustrative purposes only,

Fig. 1 is a side elevation of a rotary disk bit 5 of the invention.

Fig. 2 is a partly sectioned front elevation corresponding to Fig. 1.

Fig. 3 is a horizontal cross section looking upwardly from the plane indicated by the line 3—3 10 of Fig. 2.

Fig. 4 is an enlarged fragmentary cross section on a plane represented by the line 4—4 of Fig. 2.

Fig. 5 is an elevational view of a fragment of 15 a cutter disk having an alternative form of teeth of the character comprehended by the invention.

Fig. 6 is a partly sectioned elevational view similar to Fig. 2, but showing an alternative form of my invention.

Fig. 7 is a partly sectioned elevational view 20 similar to Fig. 2, showing an alternative form of my device in which a supporting bar of circular cross section is employed and in which the bearing members are prevented from rotation by interengagement with the vertical legs of the drill 25 body.

In the simple embodiment of my invention, as illustrated by Figs. 1, 2, and 3, I employ a bit body 11 having an upper body portion 12 equipped with means, such as a threaded pin 13, 30 for attaching the bit body 11 to the lower end of a string of drill pipe, there being a central opening extending downwardly from the top of the threaded pin 13 and into the body 11 forming a main fluid chamber or passage 14 which communicates with the interior of the drill pipe to which the body 11 is attached. The bit body 11 has a center leg 15 and side legs 16 which extend downwardly and preferably vertically therefrom, as best shown in Fig. 2, these legs being so spaced that cutter channels or spaces 17 are formed between the center leg and the side legs. 35

Laterally extending through openings 20 in and near the lower ends of the legs 15 and 16 is 40 a rugged supporting bar 21 which is non-circular in cross section so as to be non-rotatable in the openings 20 which are also non-circular in cross section. As shown in Fig. 1, I prefer to make the bar 21 of hexagonal cross section and to make 45 the openings 20 of the legs 15 and 16 in which the bar 21 is received of corresponding hexagonal cross section. In the practice of the invention the openings 20 may be conveniently 50 broached to desired form from circular holes 55

which have been previously drilled laterally through the legs 15 and 16.

Supported on the bar 21 in the spaces 17 are series of bearing members 22, 23, and 24, on 5 which relatively outer and inner cutter disks 25, 26, and 27 are rotatably carried, these cutter disks 25, 26, and 27 rotating on downwardly offset axes, as shown best in Fig. 2, by reason of the downwardly relatively offset placement of 10 the bearing members 22, 23, and 24 on the supporting bar 21. In addition to being downwardly offset in the manner shown in Fig. 2, the bearing members 22, 23, and 24 are forwardly offset in the direction of rotation, as shown in Fig. 3, so 15 that the cutter disks 25, 26, and 27 will be held in forwardly offset relationship to give the forward portions of the cutting edges 30, 31, and 32 a desired lead and to prevent tracking of the following portions 33, 34, and 35 of such cutting 20 edges 30, 31, and 32 when the rotary disk bit is in operation.

A valuable feature of my invention resides in the simple means for determining the relative operating positions of the cutter disks in the 25 drill body. As previously described, the rugged supporting bar 21 is made of non-circular cross section so as to be non-rotatable in the legs 15 and 16. In a similar manner, the openings 36 through the bearing members 22, 23, and 24 30 are made of corresponding non-circular cross section so that the bearing members will not rotate on the bar 21. This makes possible the positive determination of the position of each bearing member 22, 23, or 24 as a result of placing the openings 36 therein to give the desired 35 positioning of the bearing members.

For instance, by upwardly offsetting a hole 36 in a bearing member such as 24, the placing of the bearing member on the supporting bar 40 21 will result in the axis or center of such bearing member being downwardly offset relative to the bar 21; therefore, by vertically offsetting the openings 36 of the bearing members 22, 23, and 24 in a manner such as illustrated in Fig. 45 2, a desired progressive inwardly and downwardly offset relationship of these bearing members may be accomplished. In addition to this, it is a feature of the invention to make the cutter disks 25, 26, and 27 of such diameter that the 50 respective lower portions 40, 41, and 42 of the cutting edges thereof will be progressively offset downwardly from the extreme outer cutter disk 25 toward the extreme inner cutter disk 27 of each set of cutter disks, there being three disks 55 25, 26, and 27 to each set in the present illustration of the invention, it being understood that in the practice of the invention a smaller or larger number of cutter disks may be employed in the manufacture of smaller and larger 60 sizes of bits, and it being further understood that the offset relationship of the lower portions of the cutting edges may be increased or decreased to suit existing conditions.

The invention also includes simple means 44 65 for locking the supporting bar 21 against lateral displacement in the legs 15 and 16, these locking means 44 each having a pin portion 45 and a screw-threaded portion 46, as shown in Fig. 4, the pin portions 45 entering notches 70 47 in the upper face and near the ends of the bar 21 and the threaded portions 46 thereof being received in threaded openings 48 extending laterally into the side legs 16 in alignment with the upper surface of the bar 21. With the locking means 44 in place, the pin portions

45 thereof serve as keys for preventing lateral movement of the bar 21. Large size in these locking means is not required for the reason that in the operation of the bit there is substantially no force exerted which tends to displace the bar 21 from its operative position.

The rotary disk bit of my invention is especially equipped for operation on hard formations by teeth 50 formed in the peripheries of the cutters 25, 26, and 27, or in the peripheries 10 of any selected number of these cutters as may be found advisable. To prevent tracking of the cutter teeth 50, the invention comprehends the making of teeth of differing sizes in the cutters. Illustrative of this, in Fig. 1 I have 15 shown large cutting teeth at 51 in one of the cutter disks, such as an outer cutter disk 25, smaller cutting teeth 52 in an intermediate cutter disk 26, and yet smaller teeth 53 in an inner cutter disk 27.

As shown in Fig. 5, a cutter disk 55 may be equipped with teeth 56, 57, and 58 which are all of different size and are so distributed that they will not track when the cutter disk 55 is rotated in cutting engagement with a formation. 25

Extending vertically downwardly from the main fluid passage 14 of the bit body 11 is a central fluid passage 60 which extends vertically and centrally through the center leg 15 to the lower end thereof, a part of this passage being 30 formed by a vertical hole 61 which extends through the center of the bar 21. The fluid passage 60 is in such position that it will discharge fluid directly against the central core portion formed in the formation being drilled 35 by the cutter disks placed on each side of the center leg 15, such discharge of fluid serving to displace or assist in displacing the central core portion during the drilling operation.

Extending downwardly and diagonally forwardly within the cutter body 11 are fluid passages 70 which are so positioned that they will direct flows of drilling fluid, as indicated by dotted lines 72, against the forward portions 45 of the cutting edges of the cutter disks so as to keep these cutter disks clean and to assist in the removal of the cuttings by the flow of drilling fluid which, as previously stated, is generally in the form of a mud and water mixture.

Where exceptionally hard formations are 50 encountered, it is desirable to move the inner cutter disks of the bit assembly as close to the center as possible so that substantially no core will be formed by the operation of the bit on the bottom of the hole.

In Fig. 6 I show my invention applied to a bit in which the center leg 75 is foreshortened so that the inner cutter disks 76 may be placed close together on central bearing members 77 which are held in properly spaced positions by 60 a spacing washer 78. In this form of the invention the supporting bar 79 extends between side legs 80 and is supported in working position by the engagement of its ends by the legs 80. The bar 79 is of such form that it will 65 carry the forces imposed thereon during drilling operations without undue or harmful flexure. Owing to the severe twisting strains which are applied to the inner cutters 76, they are preferably to be made of greater thickness than 70 the intermediate and outer cutters 81 and 82 which are supported on intermediate and outer bearing members 83 and 84.

In this form of the invention, the bar 79 is also non-rotatable and holds the bearing mem- 75

bers 77, 83, and 84 non-rotatably in working position. For the accomplishment of these effects the bar 79 may be made of non-circular cross section, such as hexagonal, and may be locked in regular openings 85 of similar cross section by means of locking screws 86.

Relative to the form of bit shown in Fig. 2, it has been explained that the positions of the bearing members for the cutter disks are determined by the positions of the openings in such bearing members through which the supporting bar extends, thereby making it possible in the design of the bit to establish any desired plan of cutting engagement of the lower portions of the cutter disks to meet conditions which may be encountered in different formations. In Fig. 6, the lower edges of the cutter disks 76, 81, and 82 are shown in substantially a straight line, this alignment varying from that shown in Figs. 1 and 2 and being accomplished by positioning the openings 87 of the bearing members 77, 83, and 84 so as to establish required axes of rotation for the cutter disks 76, 81, and 82.

It is a feature of this form of the device to extend a drilling fluid passage 88 substantially centrally therein through the central leg 75 so that a stream or jet of drilling fluid under pressure will be directed against the inner cutters 76, thus preventing accumulation of cuttings on or between the inner cutters 76.

In the form of the invention shown in Fig. 6, diagonal passages 89 are provided for directing streams of drilling fluid toward the forward portions of the outer cutter disks 81 and 82, these diagonal passages 89 functioning in the same manner as the diagonal passages 70 of Figs. 1 and 2.

The embodiment of the invention shown in Fig. 7 includes a bit body 90 having water passages 92 and 93 therein. Extending through the inner leg 94 and outer legs 95 of the bit body 90 is a cylindrical supporting bar 96 which is restrained from lateral movement by locking pins 97.

Outer cutters 98 and inner cutters 99 are respectively mounted on outer and inner bearing members 100 and 101, the inner bearing members 101 being forwardly and downwardly axially offset relative to the outer bearing members 100, such axially offset positions of the inner bearing members 101 being determined by the positions of the openings 102 therein. Although the axial positions of the bearing members are determined by the supporting bar 96, they, unlike the bearing members shown in the previous figures of the drawings, are not held from rotation by the supporting bar 96 which is of cylindrical form. Therefore, to prevent rotation of the bearing members, I have provided interengagement means between such bearing members and stationary parts of the bit body 90, such means of interengagement being shown in Fig. 7 as consisting of laterally extending ribs or keys 105 formed on the inner faces of the outer legs 95, these ribs or keys projecting into cooperating grooves or channels 106 in the outer bearing members 100, and ribs or keys 107 formed on the inner faces of the bearing members 101, which ribs or keys extend into key-ways or slots 108 in the center leg 94.

If desired, additional interengagement may be provided between the pairs of outer and inner bearing members 100 and 101 in the form of keys 110 projecting from the inner faces of the out-

er bearing members 100 into lateral key-ways 111 in the cooperating faces of the inner bearing members 101. In the assembly of the bit structure shown in Fig. 7, the bearing members 100 and 101 having their respective cutter disks 98 and 99 mounted thereon are moved laterally into positions between the inner leg 94 and the outer legs 95. The supporting bar 96 is then inserted through the openings in the legs 94 and 95 and the openings of the bearing members and is locked against lateral movement by the locking means 97.

In this form of the invention the bearing members are positively held against rotation by interengagement with stationary portions of the bit body and are positively held in operating position by the supporting bar 96. The bearing members and the cutter disks may be readily removed when worn and replaced by new bearing members and cutter disks with a minimum expenditure of labor.

I have herein shown simple and practical forms of my invention, but it is recognized that certain parts or elements thereof are representative of other parts, elements, or structures which may be employed in substantially the same manner to accomplish substantially the same results; therefore, it is to be understood that the invention is not to be limited to the details disclosed herein but shall have the scope set forth in the following claims.

I claim as my invention:

1. A rotary bit of the character described, including: a bit body adapted for attachment to a string of drill pipe, said bit body having a downwardly extending center leg and diametrically opposing side legs; a bar extending laterally through said legs, said bar being non-rotatable in said legs; means for locking said bar in such laterally extending position; bearing members supported on said bar in the spaces between said center and said side legs, said bearing members being non-rotatable on said bar and having openings to receive said bar so placed that said bearing members will be progressively downwardly offset from the outer bearing members toward the inner bearing members; and cutter disks supported on said bearing members.

2. A rotary bit of the character described, including: a bit body adapted for attachment to a string of drill pipe, said bit body having a downwardly extending center leg and diametrically opposing side legs; a bar extending laterally through said legs; means for locking said bar in such laterally extending position; bearing members supported on said bar in the spaces between said center and said side legs; and cutter disks supported on said bearing members, there being a central fluid passage leading downwardly through said center leg and through said bar for delivering a flow of fluid against the central core formed by said cutter disks when said bit is operated.

3. A rotary bit of the character described, including: a bit body adapted for attachment to a string of drill pipe, said bit body having a downwardly extending center leg and diametrically opposing side legs; a bar extending laterally through said legs, said bar being non-rotatable in said legs; means for locking said bar in such laterally extending position; bearing members supported on said bar in the spaces between said center and said side legs, said bearing mem-

- bers being non-rotatable on said bar and having openings to receive said bar so placed as to determine the relative axial positions of said bearing members; and cutter disks supported on 5 said bearing members, there being a central fluid passage leading downwardly through said center leg and through said bar for delivering a flow of fluid against the central core formed by said cutter disks when said bit is operated.
- 10 4. A rotary bit of the character described, including: a bit body adapted for attachment to a string of drill pipe, said bit body having a downwardly extending center leg and diametrically opposed side legs, there being aligned, laterally directed non-circular openings through the
- lower ends of said legs; a rugged supporting bar extended through said openings, said supporting bar having a cross section corresponding to said openings so as to be non-rotatable therein; cutter disks assuming tangential positions in the spaces between said center leg and said side legs; and bearing members for supporting said cutter disks, said bearing members having openings therein corresponding to the cross section of said supporting bar and so positioned relative to the centers thereof as to give a vertically offset positioning of said bearing members when said bearing members are in place on said supporting bar. 5 10

JAMES W. SPERRY. 15
